UNITED STATES PATENT OFFICE.

LEONARD R. CARLEY, OF WATERTOWN, CONNECTICUT, ASSIGNOR TO THE PATENT
BUTTON COMPANY, OF WATERBURY, CONNECTICUT, A CORPORATION OF CON-NECTICUT.

DESIGN FOR A BUTTON.

Application filed June 19, 1923. Serial No. 6,532. Term of patent 14 years.

To all whom it may concern:

Be it known that I, LEONARD R. CARLEY, a subject of His Majesty the King of Great Britain, and a resident of Watertown, county of Litchfield, and State of Connecticut, have invented a certain new, original, and ornamental Design for Buttons, of which the following is a specification.

In the accompanying drawing:

I claim:

The ornamental design for a button, as shown.

LEONARD R. CARLEY.
